CUSHION STRUCTURE

Harry M. Snyder, Hickory, N.C., assignor to Snyder Paper Corporation, Hickory, N.C., a corporation of North Carolina

Filed Aug. 31, 1964, Ser. No. 393,195

7 Claims. (Cl. 5—355)

This invention relates generally to cushions, and more particularly to a cushion for use with furniture which combines a pleasing appearance with a high degree of comfort in a composite structure which has an exceptional ability to resist set or loss of shape even after prolonged usage.

Manufacturers of seating cushions designed for use in furniture such as sofas and overstuffed chairs or the like must satisfy the furniture maker's demand for a cushion that (1) has an attractive appearance matched to the particular style of furniture with which it is used; (2) has a proper feel or "hand;" (3) has sufficient firmness or body to assure comfortable seating; and (4) will not lose its shape, become matted or acquire a "set" within the normal life expectancy of the cushion.

The advent of latex foam rubber and of synthetic foam material such as polyurethane and synthetic latex foam rubber aided cushion manufacturers in meeting these demands by providing a material which could be used alone with a cover of ticking or the like to provide a cushion which was reasonably soft and had a requisite amount of firmness, and which could be fabricated at a cost, which, even though varying with the quality of the foam used in the cushion, was always substantially less than the cost of using the down traditionally found in high-quality cushions.

The use of foam as a cushion material, however, has certain drawbacks. It was found, for example, that certain furniture styles, such as Early American, required that the cushion have a pronounced contour or crown which could not be easily formed with foam. In addition, it was found that even when layers of softer grades of foam were laminated onto a relatively firm foam base, the cushion did not have the hand found in cushions made of fibrous material and demanded by the more discriminating purchasers.

In an effort to eliminate these drawbacks, some prior art structures have adopted a compromise arrangement which employs an open ended cover piece or envelope comprising an outer surface of ticking and a layer of fibrous material held thereagainst by an inner layer of cheesecloth or the like sewn to the ticking, and a core piece of relatively firm foam inserted into the cover piece for enclosure thereby when the open end of the cover piece is sewn shut. Similarly, other prior art structures are formed by placing layers of fibrous material on opposite faces of a foam core piece and covering these layers with pieces of ticking glued or otherwise attached to the core element. These types of cushion structures, however, are also difficult to form with any pronounced contour and, even more objectionably, the fibrous material therein tends to become matted and disarranged after a period of use causing a deterioration in the cushion's appearance, comfort and hand.

The unique cushion structure of the present invention eliminates the above-noted problems of the prior art and combines the desirable qualities of foam-like materials and fibrous materials in a composite arrangement which provides a cushion that may be employed to exceptional advantage in furniture seating and which can be fabricated by a simple and inexpensive process that requires no sewing or special production apparatus.

Briefly stated, the cushion structure of the present invention is characterized by a relatively firm base element

2

having a thickness and opposed faces proportioned in relation to the cushion structure to be formed, a filler of fibrous material disposed at each of the opposite faces of the base element, and a cover member or layer consisting of relatively soft open cellular elastomeric material disposed over each of the fibrous fillers and secured continuously to the base element adjacent the perimeter of the opposite faces thereof to contain the fibrous filler thereat against disarrangement, as described in further detail below in connection with the accompanying drawings, in which:

FIG. 1 is a plan view of a cushion structure embodying the present invention; and

FIG. 2 is an enlarged sectional view taken substantially at the line 2—2 in FIG. 1.

The cushion structure of the present invention, as indicated generally by the reference numeral 10 in the drawings, comprises the previously mentioned relatively firm base element 12, with filler 14 of fibrous material disposed at each major face 16 thereof and contained thereat by a cover member or layer 18. The base element 12 is the core component of the cushion structure and is relied on to provide the requisite body and firmness therein. Preferably this base element 12 is a relatively thick and firm block of latex foam rubber in the soft to medium firmness range defined as 18 to 32 pounds Indentation or Compression Load Test value as measured by the standard ASTM Designation: D1055-62 or The Rubber Manufacturers Association—Buyers' Specification "Latex Foam." The particular firmness of the foam, the dimensions of the opposite major faces 16, and the thickness to be employed are dictated by the specifications for the particular cushion being formed. A thickness in the order of 3 to 4 inches will be suitable for most specifications. The base element core holes 20 shown in FIG. 2 characteristically result from the manner in which latex foam rubber is made. Although the core holes 20 appearing in the FIG. 2 section all extend from the upper face of the illustrated base element 12, it will be understood that additional bottom face core holes (not shown) are staggered therewith. One of the preferred materials would be pin core block foam of U.S. Patent No. 3,028,610. The advantage of the block foam is that filler fiber cannot work itself into the core holes.

Although latex foam rubber is the preferred material for the base element 12, it can be fabricated from other open cellular elastomeric material, such as polyurethane foam, if a greater tendency to set and lose shape during use is acceptable in the particular cushion structure being formed. Alternatively, any material or combination of materials which provide the requisite firmness and body could be used to form the base element 12. For example, coiled steel springs encased in a suitable cover, or rubberized horsehair are suitable materials for fabricating an adequate base element 12.

The filler 14 has a primary function of providing softness and hand to the cushion structure and, in the preferred embodiment, consists of a seating grade of polyester fiber which trade standards currently define by a weight of not less than 16 ounces per lineal yard of 32-inch lap. Suitable polyester fiber is manufactured under several trademarks, such as Dacron, Kodel and Fortrell. Other fibrous materials such as acetate fiber or cotton could also be used for the filler 14; however, polyester fiber is preferred because it has less tendency to bat down or mat, and it more nearly simulates the feel and hand of down, generally preferred as filler material except that it is much more expensive than the modern synthetics.

The cover members or layers 18 are secured to the base element 12 in a manner to be described in greater detail below to contain the fillers 14 at the opposite base element faces 16. The secured cover members 18 form

the seating surfaces of the cushion structure 10 and must be soft enough to contribute to the hand of the cushion as well as being capable, together with the fillers 14, of providing a contoured appearance. Accordingly, in the preferred embodiment the cover members 18 consist of a pad of latex foam rubber Grade RC-5 as defined in ASTM D1055-62 or in The RMA Latex Foam Buyers' Guide, approximately $\frac{1}{2}$ inch thick and having perforations 22 extending therethrough. The durability and softness of latex foam rubber make it the preferable material for the cover members 18 although, as in the case of the base element 12, other open cellular elastomeric material, such as polyurethane, or any other material having similar characteristics could be used.

The preferred cushion structure 10 is formed by first cutting a base element 12 of proper size from a stock of latex foam rubber having a suitable firmness and thickness of the order previously noted. The cut base element 12 will usually have the simple shape of a substantially rectangular block, as illustrated in the drawings, with a length and breadth proportioned in relation to the cushion structure to be formed. However, it may be cut as well with a corner ear portion or portions, where such shaping is desired for end sofa cushions or for chair cushions; or the shaping may be otherwise contoured in plan to suit the ultimate cushion use intended.

Next, a mat of filler 14 is cut from a lap supply of seating grade polyester fiber in a size and shape allowing it to be placed on a major base element face 16 with a peripheral surface portion 24 of the face 16 remaining exposed continuously about the filler 14 in a width of about 1 to 2 inches.

Then a pad is cut from a stock of latex foam rubber having the previously noted characteristics needed for the cover member 18. The shape and size of the cut pad in plan is made to correspond with that of the base element 12 with suitable allowance for edge joining of the cover member 18 thereto over the filler 14 as seen in FIG. 2. Edge joining of the cover member 18 is effected by the application of rubber cement at the cover member edges 26 and at the exposed peripheral surface portion 24 of the base element face 16 on which the filler 14 is disposed, and by placing the cover member 18 over the filler 14 and turning and pressing the edges 26 thereof on the base element peripheral portion 24 so that the tack of the previously applied cement secures the cushion structure 10 in the form illustrated by FIG. 2 after the same procedure has been carried out at both faces 16 of the base element 12. The rubber cement may be one of the many commercially available soft adhesives commonly used in the foam rubber and flexible urethane industry and may be either a solvent based type or a latex based type.

The edge joining of the cover members 18 induces a crowned shape thereto that is yieldably supported by the fibrous fillers 14 which are captured and contained thereby, so that a pronounced contouring is provided at the seating surfaces of the cushion structure 10. The degree of this contouring may be altered to a considerable extent by the sizing selected for the cover members 18 in relation to the base element 12, as the induced crowning is increased by increasing the plan size of the cover members 18 in relation to that of the base element 12 and the yieldable nature of the fibrous fillers 14 allow them to adjust in thickness substantially for effectively supporting the crowned cover members 18 despite a good deal of crowning variation.

The cushion structure 10 provided according to the present invention is thus exceptionally well adapted for contouring to a particular appearance desired, while affording excellent "hand" and body firmness for comfortable seating as well as a very advantageous durability against loss of shape. The manner in which the fibrous fillers 14 are contained by the cover member 18 effectively precludes any disarrangement of the filler material that

would cause the cushion seating surfaces to lose shape and become uncomfortable, and the result is an unusually persistent recovery of the seating surfaces to their initial contours after being sat upon. Additionally, the high degree of softness preferably provided in the cover members 18 presents an appealing feel at first contact with the cushion seating surfaces and combines nicely with the supporting fibrous fillers 14 to approximate the seating reaction of down cushioning. Because the cover members 18 have the perforations 22 extending therethrough, they are permitted to breathe readily so that the cushion structure 10 yields naturally and comfortably to a seating load, and it is only necessary to insert the cushion structure 10 within a decorative fabric cover to provide furniture cushioning of extremely good quality as to both appearance and comfort as well as durability.

This invention has been described in detail above for purposes of illustration only and is not intended to be limited by this description or otherwise except as defined in the appended claims.

I claim:

1. A composite cushion structure for use in furniture comprising a relatively firm resilient base element having thickness and opposed faces proportioned in relation to the cushion structure to be formed, a filler layer of fibrous material of substantial thickness disposed at each of said opposite faces of said base element, and a relatively thin cover layer consisting of a relatively soft open cellular elastomeric material disposed over each of said fibrous filler layers and secured directly and continuously to said base element adjacent the perimeter of each of said opposite faces thereof to contain said fibrous filler layer thereat against disarrangement.

2. A composite cushion structure for use in furniture comprising a resilient base element presenting opposite faces and consisting of a relatively firm open cellular elastomeric material, a filler layer of fibrous material of substantial thickness disposed at each of said opposite base element faces, and a relatively thin cover layer consisting of a relatively soft open cellular material disposed over each of said fibrous filler layers and secured directly and continuously to said base element adjacent the perimeter of each of said opposite faces thereof to contain said fibrous filler layer thereat against disarrangement.

3. A composite cushion structure for use in furniture comprising a resilient base element consisting of a relatively thick and firm block of open cellular elastomeric material having opposed major faces proportioned in relation to the cushion structure to be formed, a filler of fibrous material disposed at each of said opposite base element faces, and a cover member consisting of a relatively thin and soft pad of open cellular elastomeric material disposed over each of said fibrous fillers with the edge surfaces thereof secured continuously along the perimeter of the adjacent base element face to contain said fibrous filler thereat against disarrangement.

4. A composite cushion structure as defined in claim 3 and further characterized in that said base element has a thickness in the order of 3 to 4 inches and consists of latex foam rubber within the firmness range of 18 to 32 pounds compression.

5. A composite cushion structure as defined in claim 3 and further characterized in that the edge surface joining of said cover members induces a crowned shape thereto and the fibrous filler contained thereby yieldably supports said crowned shape.

6. A composite cushion structure as defined in claim 5 and further characterized in that said fibrous filler consists of a seating grade of polyester fiber.

7. A composite cushion structure as defined in claim 5 and further characterized in that each of said cover members has a thickness of approximately $\frac{1}{2}$ inch and consists of perforated latex foam rubber.
